DYNATRON OSCILLATOR

Paul O. Farnham, Boonton, N. J., assignor, by
mesne assignments, to Radio Corporation of
America, New York, N. Y., a corporation of
Delaware

Application March 5, 1932, Serial No. 597,076

2 Claims. (Cl. 250—36)

This invention relates to dynatron oscillators and particularly to oscillators capable of maintaining sustained oscillations at relatively high frequencies.

When the energizing potentials applied to a vacuum tube are properly chosen, the tube functions as a dynatron, i. e., it has a negative plate resistance over an extended range of applied voltages and will maintain sustained oscillations so long as the parallel impedance at resonance of the external plate circuit load is numerically greater than the negative plate resistance or internal plate-cathode resistance of the tube. While no difficulty is experienced in designing 10 tuned plate circuit loads for the broadcast and somewhat higher frequency ranges, it will be apparent that the problem of designing a high resistance tuned plate load becomes increasingly difficult with the higher frequencies, and it has been believed that the dynatron could not be 15 operated over the highest frequency bands.

An object of the present invention is to provide a dynatron oscillator of the type stated that will maintain sustained oscillations at frequencies higher than was previously possible. A further 20 object is to provide a dynatron oscillator including circuit elements for supplementing the dynatron action by an external coupling between the plate and control grid. More specifically, an 25 object is to provide an oscillator including a screen grid tube energized for operation as a dynatron and in which a capacitive coupling is 30 provided between the plate and control grid.

These and other objects and advantages of the 35 invention will be apparent from the following specification when taken with the accompanying drawing in which the single figure is a circuit diagram of one embodiment of the invention.

In the drawing, the reference numeral 1 identifies a screen grid tube having a plate P connected to a source of positive potential B through a tuned plate load LC and having a screen grid G₂ which is subjected to higher positive potential than that applied to the plate, for example, by 40 connection to an appropriate point on the source B. A bias resistor 2, shunted by a by-pass condenser 3, is included in the cathode load and the circuit from the cathode to the control grid G₁ is completed through a leak resistance 4. Appropriate by-pass condensers 5 are provided for returning the high frequency screen grid and plate 45 circuits to the cathode around the direct current source B.

The circuit as so far described will be recognized as a conventional dynatron oscillator cir-

cuit which will generate oscillations so long as the resistance of the plate load, at its resonant frequency, is numerically greater than the internal plate cathode impedance or negative resistance of the tube. In such a dynatron oscillator, an increase in control grid potential would cause an increase in plate potential, contrary to the condition in triode oscillators. Hence direct coupling from the plate to the control grid circuit, i. e., without any phase reversal, may be employed to increase the tendency toward oscillation when the plate load is tuned to high frequencies at which oscillation does not readily occur. In accordance with this invention, a small coupling capacity C₁ is provided between the plate and control grid and, preferably, the inherent capacity between G₁ and the cathode K is supplemented by shunting an external capacity C₂ between the control grid G₁ and the grounded point of the cathode circuit.

With this arrangement, the oscillating voltage developed on the plate is split by the voltage dividers C₁C₂, and a portion of the plate voltage is thus applied to the control grid in proper phase to maintain oscillations. This feedback between the plate and grid circuits raises the upper limit of the range of frequencies over which sustained oscillations will be produced but does not substantially affect the dynatron oscillation at the lower frequencies. In fact, the introduction of the capacitive coupling affords greater latitude in the design of the oscillator circuits for use at low frequencies since it effects an actual or apparent reduction in the magnitude of the negative resistance of the tube.

As will be apparent to those familiar with the design and construction of oscillator circuits, other forms of coupling may be provided to supplement the dynatron action and other types of tubes may be employed. It is to be understood that the invention is not restricted to the particular circuit herein illustrated and described, as various changes may be made in the several parts, their relative size, shape and relationship, without departure from the spirit of my invention as set forth in the following claims.

I claim:

1. In an oscillator; the combination with a vacuum tube having elements including a cathode cooperating with a control grid, an auxiliary cold electrode, and a plate; means for impressing on said auxiliary electrode a higher positive potential than on the plate for producing a negative internal plate-cathode impedance; a tuned load in the plate circuit; means for adjusting the

oscillating frequency of said tube; an external non-resonant capacity load between said control grid and said cathode; and an external capacity coupling between the plate and control grid of the tube.

2. In an oscillator, the combination with a vacuum tube having elements including a cathode cooperating with a control grid, an auxiliary cold electrode, and a plate; means for impressing on said auxiliary electrode a higher positive potential than on the plate for producing a nega-

tive internal plate-cathode impedance; a tuned load in the plate circuit; means for adjusting the oscillating frequency of said tube; means for feeding back from the plate to the control grid a desired fraction of the plate voltage without phase shift comprising a voltage divider having an external non-resonant capacity load between said control grid and said cathode, and an external capacity coupling between the plate and control grid of the tube.
